UNITED STATES PATENT OFFICE.

MILLO STODDARD, OF TAMPA, FLORIDA.

PIANO-TUNING KEY.

SPECIFICATION forming part of Letters Patent No. 729,804, dated June 2, 1903.

Application filed September 23, 1902. Serial No. 124,588. (No model.)

To all whom it may concern:

Be it known that I, MILLO STODDARD, a citizen of the United States, residing at Tampa, in the county of Hillsboro and State of Florida, have invented a new and useful Piano-Tuning Key, of which the following is a specification.

The invention relates to devices of that class employed for tuning stringed instruments, especially pianos, and has for its principal object to provide a tuning implement of simple and effective construction which may be readily placed in position and moved along the wrest-plank for engagement with the tuning-pins.

A further object of the invention is to provide an instrument of this character with gearing so arranged as to permit the operator to place the strings under any tension without difficulty and with the exercise of comparatively small force, and, further, to provide the device with a support by which it may be properly held in position and at the same time permit the ready adjustment from pin to pin as the tuning progresses.

A further object is to provide a tuning-key with gearing connections so arranged as to permit of very delicate adjustment of the tuning-pins.

With these and other objects in view the invention consists in the novel construction and arrangement of parts hereinafter described, illustrated in the accompanying drawings, and particularly pointed out in the appended claims, it being understood that various changes in the form, proportions, size, and minor details of the structure may be made without departing from the spirit or sacrificing any of the advantages of the invention.

In the accompanying drawings, Figure 1 is a perspective view of a piano-tuning instrument constructed in accordance with my invention. Fig. 2 is a side elevation of a portion of the instrument, illustrating the gearing connections between the operating-handle and the pin-engaging key. Fig. 3 is an end elevation of the same. Figs. 4 and 5 are detail views, on an enlarged scale, of the clamp by which the device is secured in position. Fig. 6 is a plan view of a portion of the frame, partly in section, on the line 6-6 of Fig. 3.

Similar numerals of reference are employed to indicate corresponding parts throughout the several figures of the drawings. 55

The device forming the subject of the present invention comprises, in general, a frame, a key or wrench carried thereby and connected by gearing to an operating-handle, an elongated rod supporting said frame and of 60 a length about equal to one-half of the length of the string-frame of the piano, and a clamp loosely connected to the rod and adapted to be attached to one of the tuning-keys.

The carrying-clamp comprises a pair of 65 spring-jaws 1, having recesses in their inner faces for the reception of the angular end portion of a tuning-key, a thumb-screw 2 being passed through the jaws to permit the clamping of the latter on any desired key. At the 70 top of the clamp is a circular stud 4, having rounded upper and lower shoulders, the upper end of the stud being reduced in diameter and threaded for the reception of a nut 5.

6 designates a round bar, which may be 75 formed in sections, if desired, and at one end of said bar is an opening 7 for the reception of the pin or stud 4, the nut being screwed in place after the pin is passed through the opening, but the connection between the bar 80 and pin being sufficiently loose to permit a considerable range of movement of the bar, the latter being freely movable in a circular path with the pin as a center, while the pin is of less diameter than the opening 7 to permit free movement of the bar from and toward the wrest-plank. 85

10 designates an angular frame having an opening for the reception of the bar 6, said frame being freely movable longitudinally of 90 the bar in order to permit its adjustment over any tuning-pin within the length of the bar. This frame is provided with a bearing for the support of a spindle 12, having at its lower end a socket 13 for the reception of the tuning-pins. The upper end of the spindle is provided with a small miter-gear 14, intermeshing with a similar gear 15 on a pin or stud projecting from the frame 10. The gear 15 is preferably formed integral with a small 95 worm-wheel 16, intermeshing with a worm 17 on a shaft 18, having at its upper end an operating-handle 19. The shaft 18 is adapted to a removable bearing formed by a collar 20, 100

- which passes through a suitable opening in the upper portion of the frame 10 and is confined in place by a pin 21, the collar serving also to maintain the worm in proper position.
- 5 The worm-gearing permits the operator to turn the tuning-pins to any desired extent with the exercise of but little force, and the construction and arrangement of the frame are such that the operator may engage tuning-pins near the ends of the wrest-plank and close to the piano-casing at points where the casing usually interferes with the tuning implement in ordinary use.
- In using the implement the clamp is first secured to a tuning-pin near the center of the string-frame, and the tuning-pins, starting from the center, are successively engaged in the socket 13 and turned until the strings are at the desired tension. The loose connection 15 between the clamp and the rod 6 permits the ready engagement and disengagement of the socket with successive pins, while the rod prevents the turning of the frame 10 when the handle 19 is turned.
- 20 25 The implement is of simple and economical construction and may be readily carried from place to place, the rod being preferably made of a number of jointed sections to facilitate transportation.
- 30 35 In order that the device may be conveniently used for stringing where the tuning-pin can be rapidly turned with but little exertion, a metal-lined socket 25 is formed at one end of the operating-handle 19 for the reception of the tuning-pins. When used for stringing, the frame 10 and the parts carried thereby are removed from the rod and the socket 25 placed over the pin and used in the ordinary manner.
- 40 Having thus described my invention, what I claim is—
1. The combination in a tuning instrument, of a tuning-key, a frame carrying the same and provided with a longitudinally-disposed 45 guiding-opening, an operating - handle also carried by the frame, gearing connecting the handle and key, a rod passing through the guiding-opening of the frame, and means for supporting said rod.
- 50 2. The combination in a tuning implement, of a rod, a supporting means for the rod, a frame adjustable longitudinally of the rod, a spindle carried by the frame and provided with a pin-receiving socket, a handled spindle also supported by the frame, and worm- 55 gearing connecting the two spindles.
3. The combination in a tuning implement, of a rod, a supporting means for the rod, a frame guided by and adjustable longitudinally of said rod, a spindle adapted to the 60 frame and provided with a pin-receiving socket, a handled spindle, a worm thereon, a worm-wheel supported by the frame and intermeshing with said worm, and miter-gearing connecting the worm-wheel to the spindle 65 having the pin-receiving socket.
4. The combination in a tuning instrument, of a clamp adapted to be secured to a portion of the instrument to be tuned, a rod swiveled to the clamp, a frame provided with 70 a rod-receiving opening, and a tuning-key carried by said frame.
5. The combination in a tuning implement, of a clamp comprising a pair of spring-jaws having recesses for the reception of a tuning- 75 pin, a thumb-screw for closing the clamping-jaws, a pin carried by said jaws and having an upper threaded portion of reduced diameter, a rod or bar having an opening adapted for the reception of said pin, a securing-nut 80 adapted to the threaded portion of the pin, a frame having a guiding-opening for the reception of the rod, a spindle carried by the frame and provided with a pin-receiving socket, a handled spindle, a worm thereon, a 85 collar surrounding the spindle and serving to maintain the worm in proper position, a stud carried by the frame, a worm -wheel mounted on the stud and intermeshing with said worm, and miter-gearing connecting the 90 worm-wheel to the spindle having the pin-receiving socket.
6. The combination in a tuning implement, of a tuning-key, a frame carrying the same, an operating-handle also carried by the frame 95 and having a socket for the reception of a tuning-pin when stringing, and gearing connecting the handle and key, substantially as specified.
- In testimony that I claim the foregoing as my own I have hereto affixed my signature in the presence of two witnesses.
- MILO STODDARD.
